United States Patent Office

Des. 227,492

Patented June 26, 1973

227,492

TOY MOTORCYCLE

Larry R. Wood, Redondo Beach, Calif., assignor to
Mattel, Inc., Hawthorne, Calif.

Filed Aug. 7, 1972, Ser. No. 278,687

Term of patent 14 years

Int. Cl. D21—01

U.S. Cl. D34—15 A

FIG. 1

FIG. 2

FIG. 3

FIG. 1 is a left side elevational view of the toy motorcycle showing my new design;

FIG. 2 is a top plan view thereof;

FIG. 3 is a front elevational view thereof;

FIG. 4 is a right side elevational view thereof;

FIG. 5 is a bottom plan view thereof; and

FIG. 6 is a rear elevational view thereof.

I claim:

The ornamental design for a toy motorcycle, as shown.
